UNITED STATES PATENT OFFICE

Jacob V. Dyrr, Bell, Calif., assignor to International Harvester Company, a corporation of New Jersey

Application August 10, 1942, Serial No. 454,202

8 Claims. (Cl. 55—83)

This invention relates to a tandem harrow. More specifically it relates to a means for permitting the turn of a tandem harrow.

More specifically it relates to a means for permitting the turn of a tandem harrow.

In a tandem harrow composed of a pair of front gangs and a pair of rear gangs, turn is facilitated by a pivotal connection between the front and rear frames to which the front and rear gangs are respectively connected. There is no great difficulty in turning such a harrow on level ground, but on ground having side slope there is considerable tendency for the rear pair of gangs not to follow the front gangs in the turn but to slide down-hill. The present invention has to do with a construction which will overcome this tendency.

An object of the present invention is to provide an improved tandem harrow.

Another object is the provision of an improved connection between the gangs of a tandem harrow which will facilitate turning the harrow.

A further object is to provide a locking or holding means employable for the backing of a harrow, the parts of which are connected for easy turning.

According to the present invention, the front and rear draft frames associated respectively with the front and rear gangs of a tandem harrow are connected with one another in a pin-and-slot connection and by means of flexible elements at opposite sides of the pin-and-slot connection.

In the drawings:

Figure 1 is a plan view of the harrow of the present invention in working position;

Figure 2 is a side view of the harrow in transport position;

Figure 3 is a sectional view taken on the lines 3-3 of Figure 1; and

Figure 4 is a sectional view taken on the lines 4—4 of Figure 2.

The harrow of the present invention includes a pair of front gangs 10 and a pair of rear gangs 11 oppositely angled in working position, as shown in Figure 1. A front frame 12 is connected to the front gangs 10 and this front frame comprises essentially a central longitudinal member 13 having a forward portion 14 at one level and a rearward portion 15 at a somewhat higher level above the gangs 10 as indicated in Figure 2. The portions 14 and 15 are connected by an intermediate bent portion 16. Secured to the forward portion 14 is a short transverse piece 17 to the ends of which are connected short links 18 extending to the inner ends of the front gangs 10 so as to be connected therewith at points no

extending through an elongated slot 48 in the rear portion 15 of the forward draft frame 12. A holding and latch member 49 is pivotally mounted between side pieces 50 secured to the rear portion 15 of the front frame 12, and in the position shown in Figure 3 extends rearwardly from the side pieces 50 so as substantially to abut the extreme front end of the central longitudinal member 33. There is an upstanding projection 51 secured to the holding member 49, and connected to the projection 51 is a latch control member 52, which extends across and in contact with a pin 53 extending between the sides of the U-shaped member 21. The lower side of the control and latch member 52 carries an element 54, which is adapted to engage the pin 53 and thereby to hold the holding and latch member 49 in the raised position of Figure 2. This is accomplished by pull upon the cord 55 attached to the forward end of the control member 52. When the holding member 49 is in the raised position of Figure 2, the bolt 46 may slide in the slot 48, and thus the rear frame 31 may have both a sliding and a pivoting movement with respect to the front frame 12.

For operation of the harrow on level ground, simple pivotal connection between the draft frames associated with the front and rear gangs of the harrow would be sufficient, for it would not be difficult to make the rear gangs 11 properly follow behind the front gangs 10. However, when the harrow is operated upon ground having a side slope, the rear gangs may slide down-hill, and thus the gangs must be connected in other ways. As seen in Figure 1, there is secured near but somewhat spaced from the rear end of the rear portion 15 of the front frame 12 a transverse member 56 having openings 57 therein. A similar transverse member 58 having openings 59 therein is secured to the forward portion 35 of the central longitudinal member 33 of the rear draft frame. The transverse member 58 is braced by diagonal pieces 60a. A pair of chains 61 extends between the transverse members 56 and 58 at opposite sides of the bolt or pin 46 and the slot 48 and is connected at its ends in the openings 57 and 59 in the transverse members. When the harrow is operated upon ground with a side slope, the normal tendency for the rear gangs not to follow properly behind the front gangs but to slide down-hill is resisted by the chains 60 and the transverse members 56 and 58. For example, when the down-hill is to the left, then the chain to the right stays taut and resists the tendency of the rear gangs to slide down-hill and compels them to be dragged directly behind the front gangs. If down-hill is to the right, then the chain 60 at the left stays taut and resists the tendency of the rear gangs to slide down-hill. The connection of the front and rear frames by means of the pin or bolt 46 in the slot 48, which permits both a sliding and a pivoting of the frames, facilitates the turning, for it counteracts to some degree the tendency of the rear gangs due to the chains 60 to be merely dragged around behind the front gangs and permits some pivoting action. Figure 1 shows the chain 60 connected to the intermediate holes 57 and 59. If the harrow is operated upon level or substantially level ground, the chain 60 may be moved inwardly to the innermost sets of holes 57 and 59 so as to be virtually without effect upon turning. If the harrow is operated upon ground of an excessive side slope, the chains 60 are moved to the outermost sets of holes 57 and 59.

When the harrow is to be transported, the gangs must be straightened so that the front gangs are in line with one another and are parallel with the rear gangs. When this is to be done, the latching element 54 is released from the pin 53 so that the holding member 49 is brought into the position shown in Figure 3, in which it substantially prevents sliding movement of the rear draft frame with respect to the front frame. 5 Then the latch 26 is released from engagement with the teeth 25 on the sliding draft head 23, and the harrow is backed by an application of rearward force to the sliding draft head until the gangs are straightened. The rearward slide of 10 the draft head 23 on the front frame 12 causes a rearward movement of the outer ends of the front frame 10 through the action of the long 15 links 28. The rearward projections 45 on the inner ends of the front gangs and the long links 20 43 connected near the outer ends of the rear gangs 11 causes a rearward movement of the outer ends of the front gangs 10 to effect a forward movement of the outer ends of the rear gangs 11. When this happens the holding member 49, positioned as shown in Figure 3, prevents 25 any forward movement of the rear draft frame 31 and thus straightening of the rear gangs is accomplished. The chains 60 prevent during 30 backing of the harrow any tendency of the rear gangs to move to one side of the front gangs.

From the foregoing description it will be seen that a new and novel tandem harrow construction has been provided. This novel construction involves means which facilitates operation of the harrow upon ground having a side slope. The front and rear frames of the harrow have a sliding and pivoting connection, and there are flexible elements provided on opposite sides of the sliding and pivoting connection which counteracts the tendency of the rear gangs to run down-hill.

The intention is to limit the invention only within the scope of the appended claims.

What is claimed is:

1. In a tandem harrow comprising a pair of front gangs, a pair of rear gangs, a front draft frame connected to the front gangs, and a rear draft frame connected to the rear gangs, the combination therewith of means connecting the draft frames in a longitudinal slide and vertical pivot connection providing relative fore-and-aft movement and relative pivoting between the frames, and flexible laterally spaced draft elements connecting the frames on opposite sides of and spaced from the slide-and-pivot connection whereby draft on the sliding and pivoting connection and tension in one of the flexible draft elements resists lateral movement of the rear draft frame during straight-ahead movement of the harrow and whereby the sliding connection permits angular movement of the rear frame relative to the front frame for turning movement of the harrow.

2. In a tandem harrow comprising a pair of front gangs, a pair of rear gangs, a front draft frame connected to the front gangs, and a rear draft frame connected to the rear gangs, the combination therewith of a portion of one draft frame formed with a longitudinal slot therein, a pin secured to the other draft frame and sliding in the slot, the pin and slot providing relative fore-and-aft movement and relative pivoting between the frames, and flexible laterally spaced draft elements connecting the frames on opposite sides of and spaced from the slot and

pin whereby draft on the sliding and pivoting connection and tension in one of the flexible draft elements resists lateral movement of the rear draft frame during straight-ahead movement of the harrow and whereby the sliding connection permits angular movement of the rear frame relative to the front frame for turning movement of the harrow.

3. In a tandem harrow comprising a pair of front gangs, a pair of rear gangs, a front draft frame connected to the front gangs, and a rear draft frame connected to the rear gangs, the combination therewith of a portion of the front draft frame formed with a longitudinal slot therein, a pin secured to the rear draft frame and sliding in the slot, the pin and slot providing relative fore-and-aft movement and relative pivoting between the frames, and flexible laterally spaced draft elements connecting the frames on opposite sides of and spaced from the slot and pin whereby draft on the sliding and pivoting connection and tension in one of the flexible draft elements resists lateral movement of the rear draft frame during straight-ahead movement of the harrow and whereby the sliding connection permits angular movement of the rear frame relative to the front frame for turning movement of the harrow.

4. In a tandem harrow comprising a pair of front gangs, a pair of rear gangs, a front draft frame connected to the front gangs, and a rear draft frame connected to the rear gangs, the combination therewith of a portion of one draft frame formed with a longitudinal slot therein, a pin secured to the other draft frame and sliding in the slot, transverse members secured to the front and rear draft frames and having attaching portions at spaced points thereon, and flexible laterally spaced draft elements extending between the transverse members at opposite sides of and spaced from the slot and pin and connectable with the transverse members at the various attaching portions to hold the flexible elements either near or spaced from the slot and pin whereby draft on the sliding and pivoting connection and tension in one of the flexible draft elements resists lateral movement of the rear draft frame during straight-ahead movement of the harrow and whereby the sliding connection permits angular movement of the rear frame relative to the front frame for turning movement of the harrow.

5. In a tandem harrow comprising a pair of front gangs, a pair of rear gangs, a front draft

frame connected to the front gangs, and a rear draft frame connected to the rear gangs, the combination therewith of means connecting the draft frames in a slide-and-pivot connection, manual means for eliminating the slide from the slide-and-pivot connection for adjustment of the harrow gangs by backing, and flexible elements connecting the frames on opposite sides of the slide-and-pivot connection.

6. A tandem harrow comprising a front frame, a pair of front gangs adjustably connected thereto, a rear frame, a pair of rear gangs connected thereto, the frames including central longitudinal members, the one frame having an elongated slot, the other frame having a pin fitting into the slot for a sliding and pivoting connection of the frames, a latch member cooperating with the longitudinal members to prevent sliding between the frames, and flexible elements connecting the front and rear frames at opposite sides of the slot and pin.

7. A tandem harrow comprising a front frame, a pair of front gangs adjustably connected thereto, a rear frame, a pair of rear gangs adjustably connected thereto, the frames including central longitudinal members, the one frame having an elongated slot, the other frame having a pin fitting into the slot for a sliding and pivoting connection of the frames, a latch member cooperating with the longitudinal members to prevent sliding between the frames, transverse members secured to the longitudinal members, and flexible elements connecting the transverse members at opposite sides of the slot and pin.

8. A tandem harrow comprising a front frame, a pair of front gangs adjustably connected thereto, a rear frame, a pair of rear gangs adjustably connected thereto, the frames including central longitudinal members, the one frame having an elongated slot, the other frame having a pin fitting into the slot for a sliding and pivoting connection of the frames, a latch member cooperating with the longitudinal members to prevent sliding between the frames, transverse members secured to and extending from opposite sides of the longitudinal members and having attaching portions at spaced points of the transverse members, and flexible elements extending between the transverse members at opposite sides of the slot and pin and being connectable at the various attaching portions to position the flexible elements either near or spaced from the slot and pin.
